UNITED STATES PATENT OFFICE.

THOMAS ADAMS, OF PHILADELPHIA, PENNSYLVANIA, ASSIGNOR TO THE HENSEL-CALLADAY COMPANY, OF SAME PLACE.

DESIGN FOR DRESS-TRIMMING.

SPECIFICATION forming part of Design No. 21,504, dated April 26, 1892.

Application filed April 4, 1892. Serial No. 427,754. Term of patent 3½ years.

To all whom it may concern:

Be it known that I, THOMAS ADAMS, a citizen of the United States, and a resident of Philadelphia, Pennsylvania, have invented a new and original Design for a Dress-Trimming, of which the following is a specification.

My design for a dress-trimming is fully shown in the accompanying drawings, in which—

Figure 1 represents a perspective view of a piece of the trimming, and Fig. 2 is a sectional view of the same.

The design comprises the cylindrical chenille strip A and a tape B, projecting radially

from one side of the same. The cylindrical chenille strip has rings or bands *a* extending around the strip, except at the point where the tape B joins the same.

I claim—

The design for a dress-trimming, substantially as described, and as shown in the accompanying drawings.

In testimony whereof I have signed my name to this specification in the presence of 25 two subscribing witnesses.

THOMAS ADAMS.

Witnesses:

WILLIAM D. CONNER,
HARRY SMITH.
